(57) CLAIM

The ornamental design for a combined applique and quilting pattern applied to bags as shown and described.

DESCRIPTION

FIG. 1 is a perspective view of a combined applique and quilting pattern applied to bags of my new design from the front, left;

FIG. 2 is an elevational view thereof from the front;

FIG. 3 is an elevational view thereof from the left; and,

FIG. 4 is an elevational view thereof from the right. The dashed lines in FIGS. 1-4 show stitching that is part of the claimed design.

The dotted lines in FIGS. 1-4 show unclaimed environmental structure and portions of the combined applique and quilting pattern applied to bags that form no part of the design.

The lightly drawn unbroken lines in the lower right diagonal portions of FIGS. 1-4 show shading from a light source at a forty-five degree angle from the upper left to lower right.
